DUMPING GRATE

Application filed June 13, 1928. Serial No. 285,181.

This invention relates to dumping grates for coal burning furnaces, and has particular reference to certain improvements in the grate dumping mechanism therefor.

The invention primarily comprehends an improved dumping mechanism and control which removes from the ash pit all obstructions which may be subject to injury, distortion or breakage by the ash removing implements.

As a further feature, the invention comprehends an improved dumping mechanism control for the separate dumping sets, by virtue of which the dumping operation may be accomplished from one side of the furnace, thereby centralizing the dumping operation control.

Other objects of the invention reside in the comparative simplicity of construction and mode of operation of the grate, the economy with which it may be produced and installed and the general efficiency derived therefrom.

With the above recited and other objects in view, reference is had to the following description and accompanying drawings, in which there is exhibited one example or embodiment of the invention, while the claims define the actual scope of the same.

30 In the drawings:

Figure 1 is a sectional plan view through a furnace equipped with a dumping grate assemblage constructed in accordance with the invention.

35 Figure 2 is a sectional view taken approximately on the line 2—2 of Figure 1 and illustrating the grate assemblage and its control in side elevation.

Figure 3 is an enlarged fragmentary sectional view taken approximately on the line 3—3 of Figure 1.

Figure 4 is a transverse sectional view taken approximately on the line 4—4 of Figure 1.

5 Figure 5 is a perspective view of one of the grate elements removed.

Figure 6 is a fragmentary horizontal sectional view taken approximately on the line indicated at 6—6 in Figure 2.

Referring to the drawings by characters of

reference, the grate assemblage includes a rectangular supporting frame 10 which is supported in the usual manner by legs 11 which depend from the opposite side rails 12 thereof. The cradle members designated generally by the reference character 13, of which there are two illustrated, each consist of a widely spaced pair of side rails 14 and 15 connected adjacent the opposite ends by web plates 16 spaced inwardly from the opposite ends of the side rails. The cradles are mounted transversely within the supporting frame 10 for rocking movement by means of outwardly projecting bearings 17 on the web plates which engage over inwardly projecting trunnions 18 on the side rails 12. The rocking of each cradle from a horizontal to a tilted position or vice versa is accomplished by means of the interengagement of a sector shaped worm rack 19 and worm pinion 20, the former being connected to and carried by each cradle and projecting laterally into an arcuate slot 21 partially formed in the side rail of the frame and in the leg structure. The worm pinion 20 is mounted in a notch 22 in the leg 11, which notch communicates with the arcuate slot 21 and said pinion is keyed or otherwise secured to an operating shaft 23 which extends forwardly through the leg to the front of the furnace. Under this construction and arrangement, it is obvious that the dumping control is disposed in a position where it is entirely outside of the confines of the ash pit and presents no obstruction to the use of implements for effecting the removal of the ashes from the pit. It is also further obvious that within the scope of the invention the shaft 23 which is connected to the pinion 20 of the rearmost cradle may extend axially through the pinion 80 which controls the foremost cradle and also through a hollow shaft 24 which is operatively connected with the pinion 20 of the front cradle. This allows separate control of the cradles which are disposed in the same axis and at a centralized point at one side of the furnace. It is obvious that the forward end of the shaft 23 will protrude from the forward end of the hollow shaft 24 and be squared or otherwise formed at 25 with means for accommodating an oper-

ating handle 26 while the forward end of the tubular shaft 24 will be provided with a squared or otherwise formed portion 27 for a similar purpose.

- 6 The intermediate grate elements 30 are each provided with depending locking lugs 31 which are of a width approximately equal to the spacing between the cradle rails 14 and 15 so as to snugly fit therebetween for rendering accidental displacement practically impossible. This construction of connection between the grate elements precludes their removal from the cradle except when withdrawn directly at a right angle. It will also be observed that the outermost grate bars 32 are provided with only a single depending lug 31, as the outermost lug is dispensed with, due to the fact that the lower edge of the grate bar rests directly upon the bearings 17. 10 Each cradle is provided with a slam lug 33 adapted to engage with a stop element 34 projecting inwardly from the side rail of the supporting frame. This insures a proper horizontal arrangement of the grate bars after the same are moved back to normal position following the dumping operation. In practice, the inner surfaces 35 and 36 of the side rails 14 and 15 of the cradle members may converge slightly downwardly, as clearly illustrated in Figure 3, and the front and rear edges 37 and 38 of the locking lugs 31 will be correspondingly inclined downwardly and inwardly to facilitate the application of the grate bars to the cradle. 15
- 20 25 30 35

35. What is claimed is:

1. In a dumping grate, a rectangular supporting frame, a plurality of grate units rockably mounted in the frame and disposed in forwardly and rearwardly spaced relation 40 and operating mechanism for selectively dumping the units, said mechanism underlying and being disposed in a vertical plane passing through one side of the grate supporting frame.
- 45 2. In a dumping grate, a rectangular supporting frame, a plurality of grate units rockably mounted in the frame and disposed in forwardly and rearwardly spaced relation and operating mechanism for selectively dumping the units, said mechanism underlying and being disposed in a vertical plane passing through one side of the grate supporting frame, said mechanism including a tubular shaft for the foremost grate unit, a shaft for the rearmost grate unit extending through the tubular shaft and a worm segment and pinion connection between each shaft and grate unit. 50 55
- 60 65 3. In a dumping grate, a rectangular supporting frame, a plurality of grate units rockably mounted in the frame and disposed in forwardly and rearwardly spaced relation and operating mechanism for selectively dumping the units, said mechanism underlying and being disposed in a vertical plane

passing through one side of the grate supporting frame, said mechanism including a tubular shaft for the foremost grate unit, a shaft for the rearmost grate unit extending through the tubular shaft and a worm segment and pinion connection between each shaft and grate unit, said shafts and the worm segment and pinion being disposed in cutaway portions of one of the sides of the supporting frame. 70 75

4. A dumping grate structure for furnaces including a rectangular supporting frame, a grate supporting cradle, an operating mechanism therefor including a shaft extending inwardly from the front wall of the furnace 80 and disposed in a vertical plane passing through one side of said grate supporting frame, a worm pinion secured to said shaft, and a worm rack segment meshing with the pinion and carried by the grate cradle. 85

5. A dumping grate structure for furnaces including a rectangular supporting frame, a grate supporting cradle, an operating mechanism therefor including a shaft extending inwardly from the front wall of the furnace 90 and disposed in a vertical plane passing through one side of said grate supporting frame, a worm pinion secured to said shaft and a worm rack segment meshing with the pinion and carried by the grate cradle, said 95 side wall of the supporting frame having an arcuate recess which accommodates the worm rack segment which extends laterally thereinto from its juncture with the grate cradle. 100

6. A dumping grate structure for furnaces including a rectangular supporting frame having supporting legs depending from the side rails thereof, a grate supporting cradle, an operating mechanism therefor including a shaft extending rearwardly from the front wall of the furnace and disposed in a vertical plane passing through one side rail of the grate supporting frame and below said side rail, a worm pinion secured to said shaft, a 110 worm rack segment meshing with said pinion and carried by and projecting laterally from the grate cradle, the said side rail of the grate supporting frame and supporting leg defining an arcuate recess within which the worm 115 rack segment works, and said leg being further provided with a notch communicating with the arcuate slot and accommodating the worm pinion, said supporting leg being further provided with a horizontal bore extending therethrough to accommodate the shaft of the operating mechanism. 120
